UNITED STATES PATENT OFFICE

129,932

DESIGN FOR AN ELECTRIC LAMP

Howard H. Smith, Lock Haven, Pa.

Application July 29, 1941, Serial No. 102,541

Term of patent 7 years

To all whom it may concern:

Be it known that I, Howard H. Smith, a citizen of the United States, residing at Lock Haven, in the county of Clinton and State of Pennsylvania, have invented a new, original, and ornamental Design for an Electric Lamp, of which the following is a specification, reference being had to the accompanying drawing, forming part thereof.

Figure 1 is a view in front elevation of an electric lamp embodying my new design.

Figure 2 is a top plan view thereof, and

Figure 3 is a view thereof in end elevation.

I claim:

The ornamental design for an electric lamp, substantially as shown.

HOWARD H. SMITH.
